SPORTSMAN'S LEG PROTECTOR

Richard J. Garcia, Torrance, Calif. (16281 Serenade Lane, Huntington Beach, Calif. 92647)

Filed Nov. 30, 1966, Ser. No. 4,865

Term of patent 14 years

(Cl. D2—27)

FIG. 2.

FIG. 1 is an elevational plan view of a sportsman's leg protector showing my new design.

FIG. 2 is a transverse sectional view taken on the line 2—2 of FIG. 1.

I claim:

The ornamental design for a sportsman's leg protector, substantially as shown.
